(57) **CLAIM**

We claim the ornamental design for a portable receiver for a live event, as shown and described.

DESCRIPTION

FIG. 1 is a perspective view of a portable receiver for a live event according to a first variant of the present design;

FIG. 2 is a left side elevational view of the portable receiver of FIG. 1;

FIG. 3 is a top plan view of the portable receiver of FIG. 1;

FIG. 4 is a right side elevational view of the portable receiver of FIG. 1;

FIG. 5 is a rear elevational view of the portable receiver of FIG. 1;

FIG. 6 is a front elevational view of the portable receiver of FIG. 1;

FIG. 7 is a perspective view of a portable receiver for a live event according to a second variant of the present design;

FIG. 8 is a left side elevational view of the portable receiver of FIG. 7;

FIG. 9 is a top plan view of the portable receiver of FIG. 7;

FIG. 10 is a right side elevational view of the portable receiver of FIG. 7;

FIG. 11 is a rear elevational view of the portable receiver of FIG. 7; and,

FIG. 12 is a front elevational view of the portable receiver of FIG. 7.

The broken lines shown in FIGS. 1 to 12 are for illustrative purposes only and form no part of the design.
